UNITED STATES PATENT OFFICE.

WILLIAM B. HAYDEN, OF COLUMBUS, OHIO.

DESIGN FOR A HAME LINE-RING.

SPECIFICATION forming part of Design No. 19,761, dated April 15, 1890.

Application filed March 13, 1890. Serial No. 343,794. Term of patent 14 years.

To all whom it may concern:

Be it known that I, WILLIAM B. HAYDEN, a citizen of the United States, residing at Columbus, in the county of Franklin and 5 State of Ohio, have invented and produced a new and original Design for Hame Line-Rings, of which the following is a specification.

The leading feature of my design consists 10 in a hame line-ring of an oval, ellipsoidal, or elongated form, provided upon one side with a bar lying substantially parallel with the longer axis of said ring and projecting at one end beyond the end of the elliptical ring, 15 said bar being provided with two circumferential recesses located at or near the opposite ends of the bar, one of said recesses lying within and the other lying without the elliptical ring.

20 The invention will be fully understood by reference to the accompanying drawing, in which the figure is a representation of the hame line-ring embodying my design.

In the said drawing, the reference-numeral 25 1 designates a hame line-ring which is of substantially oval, elongated, or elliptical form. Upon one side of this ring is a bar 2, lying substantially parallel with the longer

axis of the ring, one end of said bar projecting beyond its point of union and beyond 30 the end of the ring. In this bar are formed two circumferential recesses 3, one being located immediately within the ring and close to one end of the bar, and the other recess being formed in or near the other end of the 35 bar, which projects beyond the end of the ring. Upon the outer or projecting end of the bar 2 is formed a boss or head 4, rounded or convex at its end.

What I claim is—

40 The design for a hame line-ring herein shown and described, the same consisting of an oval, elongated, or ellipsoidal ring provided upon one side with a bar parallel with the longer axis of the ring and having one end extending beyond the same, said bar being provided with circumferential recesses, one of which is located within and the other located without the ring, substantially as set forth.

45 In testimony whereof I have affixed my 50 signature in presence of two witnesses.

WILLIAM B. HAYDEN.
